UNITED STATES PATENT OFFICE

2,475,882

WALLPAPER CUTTER

Dominic A. De Capite, Monterey Park, Calif.

Application April 23, 1946, Serial No. 664,407

1 Claim. (Cl. 242—55.5)

1

This invention relates to a wall paper cutter, and more particularly to such a device for trimming strips of wall paper prior to application thereof.

A primary object of this invention is the provision of an improved wall paper cutter characterized by means whereby paper may be trimmed or cut in any desired length, leaving an even and aligned edge.

An additional object of the invention is the provision of means in association with such a device facilitating the accurate guiding of a cutting edge.

Still another object of the invention is the provision of such a device characterized by means whereby a portion of the curl is taken out of the paper prior to application thereof to the wall or ceiling, thus facilitating the application of paste to the paper, and further, the application of the paper to the surface being papered.

Still another object of the invention is the provision of such a device which is sturdy and durable in construction, reliable and efficient in operation, and relatively simple and inexpensive to manufacture and assemble.

Other objects will in part be obvious and in part be pointed out as the description of the invention proceeds, and shown in the accompanying drawings, wherein there is disclosed a preferred embodiment of this inventive concept.

In the drawings:

Figure 1 is a top plan view of one form of device embodying features of the instant invention, showing a roll of wall paper in position thereon, and having certain concealed portions indicated in dotted lines.

Figure 2 is an end elevational view of the device shown in Figure 1, certain parts being in a different position of adjustment, and certain concealed portions thereof being indicated by dotted lines.

Figure 3 is an elevational view of one element of construction.

Similar reference characters refer to similar parts throughout the several views of the drawings.

Referring now to the drawings, the device of the instant invention is comprised of a frame generally indicated at 10, including a rear wall portion 11, side walls 12, and a front wall 13. The wall portions are secured in related assembly, as by screws 14 forming a rectangular enclosure. The side walls 12 are provided with aligned notches or arcuate grooves 15 adapted to accommodate rotatably the ends of a shaft or

2

axle 16 provided at one end with a fixed end plate 17 and at the other end with a removable end plate 18 having a boss or collar 19 thereon adapted to be secured in position on the end of the axle, as by a pin 20, or alternatively, a set screw or the like.

Secured across the device, between the side walls 12 and substantially flush with the tops thereof is a table 21, screws 22 being utilized to secure the table to the side walls. The table 21 is positioned a slight distance from the front wall 13 to form a groove or channel 23.

Hingedly secured, as by hinge members 25 mounted on the tops of end walls 12, is a plate 15 26 provided with a transverse slotted aperture or channel 27 adapted, when the plate is folded over the table 21, to align with the groove 23.

From the foregoing, the operation of the device should now be readily understandable. A 20 roll of wall paper adapted to be utilized is positioned on the axle 16 by first removing the plate 18. After the paper has been placed in position, end plate 18 is replaced and held in position, as by means of the pin 20. The extremity 25 30 of the paper is then passed under the member 26 over the table 21, the hinge connection permitting the raising of the latter, whereupon the table 26 is folded downwardly to the position indicated in Figure 1. A requisite length of 35 the paper is then drawn out and a cutting device of any desired form, which may be a knife, a razor blade, a rotary cutting tool, or the like, is inserted in the slot 27 and drawn transversely across the paper, thus neatly and evenly severing a desired length thereof.

When it is desired to match the paper, it is preferable that the design on the paper be on the exterior of the roll, that is, facing upwardly when unrolled, but when such matching is not necessary, the design may be positioned inwardly of the roll or downwardly, whereby the plane surface is readily available for pasting when extended onto a pasting table.

Obviously, the device may be made of any desired material and in a variety of sizes to accommodate varying widths of wall paper and sizes of rolls thereof.

From the foregoing it will now be seen that there is herein provided an improved device which 50 accomplishes all the objects of this invention, and others, including many advantages of great practical utility and commercial importance.

As many embodiments may be made of this 55 inventive concept, and as many modifications may be made in the embodiment hereinbefore

shown and described, it is to be understood that all matter herein is to be interpreted merely as illustrative and not in a limiting sense.

I claim:

A paper cutting device comprising a frame including front, rear and side walls, the upper edges of said walls defining a horizontal plane, said side walls having transversely aligned arcuate grooves therein adjacent one end, an axle mounted for rotation in said grooves, a table 10 mounted between said side walls at the other end, flush with the upper edges thereof and spaced inwardly from said front wall defining a transverse channel, and a transversely slotted plate hingedly mounted in said frame for over- 15 lying said table and the upper edge of said front

wall, the slot in said plate being aligned with said channel in the horizontal position of said table.
